UNITED STATES PATENT OFFICE.

ROBERT F. DARBY, OF YONKERS, NEW YORK

DUST GUARD.

1,418,540.

Specification of Letters Patent. Patented June 6, 1922.

Application filed March 3, 1921. Serial No. 449,391.

To all whom it may concern:

Be it known that I, ROBERT F. DARBY, a citizen of the United States, and a resident of Yonkers, in the county of Westchester and State of New York, have invented certain new and useful Improvements in Dust Guards, of which the following is a specification.

The principal purpose of this invention is to produce a dust guard for axle carrying journal boxes, of extreme simplicity, cheapness of construction, durability, and automatic adjustability with respect to wear.

15 A further object is to provide a guard made essentially from a single plate of laminated material, so bonded as to resist penetration and consequent separation by submersion in lubricating oils and which 20 does not bend or warp, the sections of the plate being constrained together by a unitary resilient element acting also to maintain them in register.

These and other analogous objects are attained by the novel construction and arrangement of parts hereinafter described and shown in the annexed drawings, forming an essential part of this disclosure, and in which:—

30 Figure 1 is a front elevational view of a dust guard showing a preferred form of the invention.

Figure 2 is a side view of the same.

Figure 3 is a front view showing a modified form of guard structure.

Figure 4 is a side view thereof.

Figure 5 is a perspective view of the guard, parts being broken away to show the construction.

40 Figure 6 is a fragmentary sectional view showing the joint between sections of the guard.

Figure 7 is a fragmentary perspective view of the resilient retaining element.

45 Stated in general terms, this invention, which is an improvement on an earlier guard, patented by me October 19, 1920, 1,356,046, is formed from a single plate of uniform thickness throughout, bored for 50 the axle and having a semi-circular bottom.

The blank is grooved or recessed substantially central of its lateral edges and also

lengthwise at the top to receive therewithin the spring connection between the upper and lower sections formed by cutting the 55 guard transversely across in a plane approximately at the center of the axle opening, parallel with the top.

The joint may be made so that the contacting portions are offset in overlapping 60 relation, or each grooved to receive a key, preventing lateral movement of the main parts, but preferably the constraining means is formed with undulations filling the side 65 grooves and maintaining the upper and lower elements in vertical relation as well as holding them together and taking up any wear that may occur.

Referring now to the drawings in detail, the numeral 15 designates the upper element 70 of the guard and 16 the corresponding lower element, both being cut from an integral blank plate comprised of layers of relatively thin sheets, as wood veneer, indurated fibre or like fibrous material bonded by cement capable of resisting the effects of oil, grease, water or like solvents.

These elements, before separation, present a blank bounded by a straight top 17 having right angled side edges 18 merging into 80 a curved bottom 19.

A central longitudinal channel or groove 20 is formed from end to end in the top edge 17 of the upper element and registering channels 21 in the side edges 18, the latter 85 being of lesser depth and terminate in the curve 19.

On the center line of the blank, in a plane uniform with or slightly above that at which the radius of the curve 19 is taken, 90 is an opening 22 suited to the diameter of the axle or shaft in connection with which it is to be used.

The blank is cut across to half its thickness on one side, as at 23, in a plane slightly above the center of the opening 22 and on the other side, as at 24, in a plane below the center, the material being sheared or split between the cuts on the center of the blank's thickness, separating the same into 100 two sections, in order to take up wear and maintain contact with the axle.

At the bottoms of the side channels 21, near their ends in the lower elements 16,

are holes 26 drilled substantially radial with respect to the opening 22 and fitting these holes are the angularly bent ends 30 of a wire 31 bent to form undulations 32 and 33 5 making contact at the extremities of their loops with opposite sides of the channels 21 in such manner as to hold the sections in alignment.

Three or more of the undulations are 10 formed to engage the lower section and at least as many with the channels in the upper element 15, the wire continuing, as at 34, straight upward to curved bends 35 and then merges into a curve 36 of large radius 15 disposed in the channel 20 and making contact with its bottom, acting as a spring by which the sections are drawn together; although the spring element is shown as round, obviously a flat spring may be used. 20 In the modified form, shown in Figs. 3, 4, and 6, the blank is formed in the same manner with respect to its contour and axle opening, but the channels 20' and 21' are relatively narrower and the constraining element 34, including its ends 30 and curves 35 and 36 are adapted to fit the channels, the undulations 32-33 being omitted.

A single transverse cut 40 is made across the blank in the plane of the center of the 30 opening 22 and the separated edges are centrally grooved, as at 41 and 41' respectively in the upper and lower portions.

Tightly fitted to the grooves 41' are keys or tongues 42 of wood or like material, their 35 extending ends entering freely into the grooves 41 in the upper element 15, in such manner as to permit relative movement of the sections, towards or from each other, while the key obviously prevents side movement of the sections.

It is to be noted that the spring bands 35 are raised from the bottoms of the channels 20 or 20' an amount sufficient to permit the sections to be separated in order to freely 45 enter the axle into the opening 22, but not enough to allow the joints to become displaced or the keys 40 to entirely come out of the grooves 41 even when the curve 36 is straightened out, thus affording protection 50 from inadvertent handling in assembling.

While certain preferred embodiments of this device have been shown and described, it will be understood that changes in the form, arrangements, proportions, sizes and 55 details thereof may be made without departing from the scope of the invention as defined in the appended claims.

Having thus described my invention, what I claim and desire to secure by Letters 60 Patent is:-

1. A dust guard comprising a laminated plate cut to form a rectangular upper section and a semi-circular lower section having 65 between them an axle receiving opening and a single means passing from one side to an-

other, wholly contained within the contour of the side top edges of the laminated plate for resiliently constraining the sections in operative relation, said plate presenting a substantially level upper edge. 70

2. A dust guard comprised of a single blank of uniform thickness having channels in its upper and side edges, said blank having a central opening and cuts leading therefrom to the side edges dividing the blank into upper and lower sections, and a single constraining spring fixed at its ends in the lower section, wholly disposed in the mentioned channel, said spring being bowed at its center to rest upon the bottom of the 80 channel in the upper section. 75

3. A dust guard comprised of a single blank of uniform thickness having channels in its level upper and side edges, said blank having a central opening, upper and lower 85 sections formed by dividing said blank transversely on the center line of the opening, tenon and mortice elements formed in the adjacent edges of said elements, and a unitary spring constraining element concealed 90 in the mentioned channels circumambient said upper section and having angular ends removably engaged in said lower section permitting separation of the section. 90

4. A dust guard comprising a plurality 95 of sheets of fibrous material bonded by an impervious cement into a plate of uniform thickness containing a central opening and divided into upper and lower sections in a plane corresponding to the center of the opening, said upper section being substantially rectangular and said lower section being bounded by a curve the radius of which is taken at a point below the center of the opening, and concealed means for resiliently 100 drawing said sections towards each other. 105

5. A dust guard comprised of a single blank of uniform thickness having channels in its upper and side edges, said blank having a central opening, upper and lower sections formed by dividing said blank transversely on the center line of the opening, said lower section having a semi-circular contour gradually increasing from the sides toward the center, means for preventing 110 lateral movement of sections, and tensional means for drawing said sections together, said tensional means being concealed and protected within the mentioned channels. 115

6. A dust guard comprised of a single 120 blank of uniform thickness having channels in its upper and side edges, said blank having a central opening, upper and lower sections formed by dividing said blank transversely on the center line of the opening, a strip of spring material having its ends fixed in said lower section at the bottom of the side channels, undulating elements formed in said strip adapted to make contact with the opposite walls of the side chan- 125 130

nels, and a concavely bowed element in said strip in contact with the bottom of the channel in said upper element.

7. A dust guard comprised of a single blank of uniform thickness having channels in its upper and side edges, said blank having a central opening, upper and lower sections formed by dividing said blank transversely on the center line of the opening, tenon and mortice elements formed in the adjacent edges of said elements, a single spring constraining element disposed wholly within the mentioned channels, said elements having angular ends fixed in said lower section, and means formed with the upper portion of said element limiting the separation of said sections.

8. A dust guard comprised of a single blank of uniform thickness having channels in its upper and side edges, said blank having a central opening, upper and lower sections formed by dividing said blank transversely on the center line of the opening, a strip of spring material having its ends fixed in said lower section at the bottom of the side channels, undulating elements formed in said strip adapted to make contact with the opposite walls of the side channels in both upper and lower sections, a concavely curved element in said spring connecting the side elements thereof by convex curves, said convex curves being raised above the bottom of the top channel, and keys fitted in said lower section entering grooves in said upper section, the outward motion of said keys being limited by the height of the convex curves in said spring.

9. A dust guard comprising a flat laminated plate of uniform thickness divided into two sections having between them an axle receiving opening, and a single means wholly contained within the edges of said sections for resiliently constraining them in operative relation, said means being removable to permit separation of the sections.

10. A dust guard comprising a single laminated plate divided into two sections provided with channelled edges and having be-

tween them an axle receiving opening, and unitary means housed within the channelled edges for resiliently constraining the sections in operative relation.

11. A dust guard comprising a laminated plate cut to form a rectangular upper section and a substantially semicircular lower section having between them an axle receiving opening, and means for resiliently constraining the sections in operative relation, said means being housed at the lateral edges of the plate within the channels formed in said edges.

12. A dust guard comprised of a single blank of uniform thickness having channels in its upper and side edges, said blank having a central opening and cuts leading therefrom to the side edge dividing the blank into upper and lower sections, and constraining means fixed in the lower section, disposed in the mentioned channels.

13. A dust guard comprised of a single blank of uniform thickness having channels in its upper and side edges, said blank having a central opening, upper and lower sections formed by dividing said blank transversely on the center line of the opening, tenon and mortice elements formed in the adjacent edges of said elements, and a single constraining element concealed in the mentioned channels circumambient said upper section and fixed in said lower section, said element being removably engaged therein.

14. A dust guard comprising a plurality of sheets of fibrous material bonded by an impervious cement into a plate of uniform thickness containing a central opening and divided into upper and lower sections in a plane corresponding to the center of the opening, said upper section being substantially rectangular and said lower section being bounded by a curve, and concealed means for resiliently drawing said sections towards each other.

In testimony whereof I have signed my name to this specification.

ROBERT F. DARBY.
